229,660

BARBECUE COOKER

William A. Gammon, 3339 N. Meridian St.,
Indianapolis, Ind. 46208

Filed Aug. 26, 1971, Ser. No. 175,418

Term of patent 14 years

Int. Cl. D7—02

U.S. Cl. D7—107

FIG. 1

FIG. 2

FIG. 3

FIG. 4

FIG. 5

FIG. 6

FIG. 7

FIG. 8

FIG. 9

FIG. 10

FIG. 11

FIG. 1 is a perspective view of a barbecue cooker embodying the present invention.

FIG. 2 is a top plan view thereof as illustrated in FIG. 1.

FIG. 3 is a front elevation thereof as illustrated in FIG. 1.

FIG. 4 is a side elevation thereof as illustrated in FIG. 1.

FIG. 5 is a bottom plan view thereof as illustrated in FIG. 1.

FIG. 6 is a rear elevation thereof as illustrated in FIG. 1.

FIG. 7 is a view similar to FIG. 2 but showing the barbecue cooker in the closed position.

FIG. 8 is a view similar to FIG. 3 but showing the cooker in the position of FIG. 7.

FIGS. 9, 10 and 11 are respectively similar to FIGS. 4, 5 and 6 but show the barbecue cooker in the position of FIG. 7.

The undisclosed side of the barbecue cooker is a mirror image of the side shown, both in open and closed condition.

I claim:

The ornamental design for a barbecue cooker, as shown and described.
